Corporation, a corporation of Delaware

Application March 10, 1951, Serial No. 214,932

14 Claims. (Cl. 201—48)

1

This invention relates to interchangeable adjustable resistance units and, while it is of general application, it is particularly adapted to such units of the type adapted for assembly with other like units on a common continuous actuating shaft to form a multiple-unit adjustable resistance device.

Many electronic devices, such as electronic computers, require a large number of adjustable resistors and it is frequently required that a number of such devices be adjusted precisely in unison. When a number of such resistors are ganged together, the precision of adjustment of the resultant assembly is generally impaired by a certain amount of backlash in the coupling elements joining the individual shafts, or by lack of coaxiality in the shafts of the several resistors. Furthermore, in previous attempts to construct a single compact multiple-unit resistance device, the mechanical arrangement has been such that, if a particular resistance unit became defective in use, it has been difficult to replace the defective unit without removal and without complete disassembly of the whole device. At the same time, the resistance units utilized in such resistance devices are generally costly precision units and the several resistance units generally have different functional tapers, that is, resistance-displacement characteristics, so that, if a single unit fails, it is uneconomical to discard the entire device. It is also uneconomical to attempt to stock multiple-unit resistance devices having a large number of permutations in the functional tapers of the components of the resistance units.

It is an object of the present invention, therefore, to provide a new and improved multiple-unit adjustable resistance device which obviates one or more of the disadvantages of prior devices of this type.

It is another object of the invention to provide a new and improved multiple-unit adjustable resistance device which is characterized by one or more of the following advantages: a simple and compact construction; a precision which is not impaired by backlash or torsional deflection of the actuating shaft mechanism or lack of coaxiality in several shafts; ready interchangeability of the individual resistance units facilitating original assembly of a number of units of any desired individual functional tapers; and a construction in which the device, when assembled from a plurality of such interchangeable units, is effectively a rugged, rigid, unitary device.

In accordance with the invention, an interchangeable adjustable resistance unit adapted for

2

assembly with other like units on a common continuous actuating shaft to form a multiple-unit adjustable resistance device, comprises a cup-shaped housing having an external peripheral clamping ridge at either end thereof and an annular resistance element disposed in said housing and provided with external connection terminals. The unit also includes an electrical wiper assembly including a sleeve adapted for mounting on an actuating shaft and an electrical wiper mounted on said sleeve, said sleeve having complementary segmental extensions on opposite ends thereof for engaging similar sleeve extensions of like adjacent units, and means including a sliding contact and an external terminal for making electrical connection with the wiper.

Further in accordance with the invention, a multiple-unit adjustable resistance device includes a continuous actuating shaft, a plurality of interchangeable resistance units of the type described mounted thereon, a clamping ring engaging each pair of adjacent housing clamping ridges, and a pair of end plates including shaft-supporting bearings.

For a better understanding of the present invention, together with other and further objects thereof, reference is had to the following description taken in connection with the accompanying drawing, while its scope will be pointed out in the appended claims.

Referring now to the drawing, Fig. 1 is an exploded perspective view of an interchangeable resistance unit embodying the invention; Fig. 2 is a longitudinal elevation, partly in section along the line 2—2 of Fig. 3, of a multiple-unit adjustable resistance device comprising three units of the type illustrated in Fig. 1; while Fig. 3 is an end elevation of the device of Fig. 2 with the back end plate or the adjacent unit of a multiple-unit device removed.

Referring now more particularly to Figs. 1-3, inclusive, of the drawing, there is illustrated a multiple-unit adjustable resistance device comprising a common continuous actuating shaft 10 and a plurality of interchangeable adjustable resistance units adapted for assembly with other like units on the shaft 10. Each of the resistance units is of the type shown in Fig. 1 and comprises a cup-shaped housing 11 having external peripheral clamping ridges 11a, 11b at either end thereof. The opposed faces 11c, 11d of the ridges 11a, 11b, respectively, comprise tapered wedging surfaces for a purpose described hereinafter. The housing member 11 also has complementary peripheral surfaces 11e, 11f on opposite ends thereof for

engaging similar housings of like adjacent units. Specifically, these peripheral end surfaces are in the form of complementary steps which interlock with complementary steps of adjacent housing units. The housing 11 has a radially extending wall member 11g which serves primarily as a bearing element and positioning device for the electrical wiper assembly sleeve described hereinafter. It also serves as a closure for one end of the housing member and as a closure for the opposite end of an adjacent housing member.

Within the housing 11 is disposed an annular resistance element 12 which may be in the form of an elongated resistance strips disposed about the inner periphery of the housing 11, but insulated therefrom by the insulation sleeve 13. The resistance element 12 is provided with external terminals 14, 14 secured to a mounting block 15 of insulation material. It will be understood that the ends of resistance strip 12 are electrically connected with the terminals 14, 14 internally by connectors not shown.

The resistance unit also includes an electrical wiper assembly comprising a sleeve 16 for mounting on the shaft 10 and an electrical wiper 17 mounted on the sleeve. Specifically, a cylindrical block of insulation material 18 is rigidly secured to the sleeve 16, while a slip ring 19 is, in turn, mounted on the block 18 and supports and is electrically connected to the wiper 17. The block 18 is maintained in fixed axial position and in any predetermined or adjusted angular position on the sleeve 16 by an end plate 20 which clamps a shoulder 16a of sleeve 16 against the end of the block 18.

The sleeve 16 has complementary segmental extensions 16c, 16d on opposite ends thereof for engaging similar sleeve extensions of like adjacent units. Preferably each of these extensions consists of an approximately 180° segment and one of the extensions, for example, the extension 16d includes a pair of slots 16e forming therebetween a resilient finger 16f adjacent one edge of the segment which is sprung to engage the extending segment of an adjacent sleeve and serves to eliminate backlash between adjacent sleeves. The wiper assembly described is contained wholly within its associated housing, while the sleeve 16 has substantially the same mean axial length as the housing 11. By the term "mean axial length" is meant the length between corresponding axial end points, for example, the length of the sleeve 16 less one of the extensions. This construction ensures a close fitting assembly substantially eliminating end play between adjacent housings and wiper assemblies of the several resistance units included in a device.

The resistance unit also includes means for making a sliding contact between the wiper 17 and one of the external electrical connection terminals 21, 21. This sliding contact may comprise a pair of opposed brushes 22, 22 extending from a clamping plate 23 and engaging diametrically opposite points of the slip ring 19. The elements 22, 22, 23 are insulated from the resistance strip 12 by a strip of insulation material 24. The elements 23 and 24 and the terminal block 15 are secured to each other in position by any suitable means such as a machine screw 25.

In order to fasten together a plurality of interchangeable resistance units such as shown in Fig. 1, there is provided a clamping ring 26 engaging each pair of adjacent housing clamping ridges. Each of the clamping rings 26 is of channel-shaped cross section and somewhat narrower

in width than the adjacent clamping ridges at their roots. Each of the clamping rings 26 is also of a diameter somewhat less than that of the clamping ridges and is provided with projecting tabs 26a, 26b at either end thereof, one of the tabs, for example, the tab 26b, being tapped for engagement by a locking screw 27.

The resistance device is provided with a stiff but resilient driving connection between the shaft 10 and one of the sleeves 16, preferably the sleeve of the unit nearest the actuating member of the device. This driving connection may be in the form of a pin 28 fixedly extending through the shaft 10 so that one side of the pin extends approximately along a diameter of the shaft. This pin 28 is adapted to be engaged by the end section 16d of one of the sleeves 16, the finger 16f thereof forming a firm but resilient connection without backlash.

The resistance device includes also a pair of end plates 29 and 30 including shaft-supporting bearings 29a and 30a, respectively. The end plates 29 and 30 have a peripheral flange 29b and recess 30b, respectively, complementary to and individually engaging corresponding adjacent peripheral recess 11e and flange 11f, respectively, of the associated housing 11. The plates 29 and 30 are provided also with external peripheral clamping ridges 29c and 30c, so that they may be clamped to their respective adjacent housings by clamping rings 26. One of the end plates, for example, the end plate 30, includes means for restraining the shaft 10 against axial movement. This restraining means may take the form of a pair of C washers 31, 31 which are sprung into peripheral grooves 10a, 10a on either side of the bearing 30a. One of the end plates, for example, the end plate 30, includes provisions for mounting the multiple-unit resistance device, which means may be in the form of tapped holes 30d, 30d which may be engaged by supporting screws mounted in any convenient supporting structure.

It is believed that the operation of the multiple-unit adjustable resistance device of the invention will be clear from the foregoing description, such operation being, in general, like that of conventional elements of this type. Rotation of shaft 10 may be effected by any suitable manual or automatic actuating mechanism. Rotation of the shaft 10 is effective to rotate the series of interlocked sleeves 16 which support the slider assemblies including the wiper contacts 17 which engage their respective resistance strips 12. Due to the resilient interlocking engagement between the several sleeves 16, there is no backlash and no appreciable torsional deflection. Therefore, the wiper elements 17 of the several resistance units are adjusted accurately in unison. At the same time, the common supporting shaft 10 for the sleeves 16 maintains an accurate coaxial alignment between the wiper assemblies of the several resistance units. At the same time, the interlocking surfaces 11e and 11f of adjacent housing members 11 maintains an accurate coaxial alignment between these housing members and the resistance strips mounted therein and forms with the end plates 29 and 30 a dust-tight housing. By tightening the several clamping rings 26 on the adjacent clamping ridges of the housing 11 and the end plates 29, 30, there results a rigid unitary overall construction.

Thus it will be seen that with the construction described, there is provided a multiple-unit ad-

justable resistance device incorporating the several advantages discussed above. With this construction, resistance units of various functional tapers, for example, units having resistance-displacement characteristics following a power law, a trigonometric function, etc., may be stocked individually and thereafter assembled into devices of any desired number of units including any desired permutations of functions. Thereafter, if any of the resistance units should become defective or worn in use, it may be readily removed by loosening one or more of the clamping rings 26, replaced by a unit from stock, and readily reassembled. In addition, the phase relation between the functional tapers of the several units may be readily adjusted merely by loosening the clamping rings holding the housing of a particular resistance unit and rotating that housing until the desired phase relation is obtained. This may be effected without in any way disturbing the phase relation of other resistance units of the assembly. The relative phase relation of the wipers 17 of the several resistance units is initially adjusted at the time the assembly 17, 18, 19 is clamped in place by securing the clamping plate 20. This relative phase relation is retained even after replacement of a particular unit. On the other hand, the relative phase relation of any particular wiper assembly may be adjusted, not only by adjusting its housing, as described above, but also by loosening its individual clamping plate 20 and this will not disturb the relative phase relations of the several remaining wipers 17.

While there has been described what is at present considered to be the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An interchangeable adjustable resistance unit adapted for assembly with other like units on a common continuous actuating shaft to form a multiple-unit adjustable resistance device comprising: a cup-shaped housing having an external peripheral clamping ridge at either end thereof; an annular resistance element disposed in said housing and provided with external connection terminals; and an electrical wiper assembly including a sleeve adapted for mounting on an actuating shaft an electrical wiper mounted on said sleeve, said sleeve having complementary segmental extensions on opposite ends thereof for engaging similar sleeve extensions of like adjacent units; and means including a sliding contact and an external terminal for making electrical connection with said wiper.

2. An interchangeable adjustable resistance unit adapted for assembly with other like units on a common continuous actuating shaft to form a multiple-unit adjustable resistance device comprising: a cup-shaped housing having an external peripheral clamping ridge at either end thereof, said ridges having opposed tapered wedging surfaces; an annular resistance element disposed in said housing and provided with external connection terminals; and an electrical wiper assembly including a sleeve adapted for mounting on an actuating shaft and an electrical wiper mounted on said sleeve, said sleeve

having complementary segmental extensions on opposite ends thereof for engaging similar sleeve extensions of like adjacent units; and means including a sliding contact for making electrical connection with said wiper.

3. An interchangeable adjustable resistance unit adapted for assembly with other like units on a common continuous actuating shaft to form a multiple-unit adjustable resistance device comprising: a cup-shaped housing having an external peripheral clamping ridge at either end thereof and having complementary peripheral flanges and recesses on opposite ends thereof for engaging similar housings of like adjacent units; an annular resistance element disposed in said housing and provided with external connection terminals; and an electrical wiper assembly including a sleeve adapted for mounting on an actuating shaft and an electrical wiper mounted on said sleeve, said sleeve having complementary segmental extensions on opposite ends thereof for engaging similar sleeve extensions of like adjacent units; and means including a sliding contact for making electrical connection with said wiper.

4. An interchangeable adjustable resistance unit adapted for assembly with other like units on a common continuous actuating shaft to form a multiple-unit adjustable resistance device comprising: a cup-shaped housing having an external peripheral clamping ridge at either end thereof; an elongated resistance strip disposed about the inner periphery of said housing and provided with external connection terminals; and an electrical wiper assembly including a sleeve adapted for mounting on an actuating shaft and an electrical wiper mounted on said sleeve, said sleeve having complementary segmental extensions on opposite ends thereof for engaging similar sleeve extensions of like adjacent units; and means including a sliding contact for making electrical connection with said wiper.

5. An interchangeable adjustable resistance unit adapted for assembly with other like units on a common continuous actuating shaft to form a multiple-unit adjustable resistance device comprising: a cup-shaped housing having an external peripheral clamping ridge at either end thereof; an annular resistance element disposed in said housing and provided with external connection terminals; and an electrical wiper assembly including a sleeve adapted for mounting on an actuating shaft, a block of insulation material mounted on said sleeve, and a slip-ring and electrically connected wiper mounted on said block, said sleeve having complementary segmental extensions on opposite ends thereof for engaging similar sleeve extensions of like adjacent units; and means including a contact engaging said slip ring and an external terminal for making electrical connection with said wiper.

6. An interchangeable adjustable resistance unit adapted for assembly with other like units on a common continuous actuating shaft to form a multiple-unit adjustable resistance device comprising: a cup-shaped housing having an external peripheral clamping ridge at either end thereof; an annular resistance element disposed in said housing and provided with external connection terminals; and an electrical wiper assembly including a sleeve adapted for mounting on an actuating shaft and an electrical wiper mounted on said sleeve, said sleeve having complementary segmental extensions on opposite ends thereof for engaging similar sleeve extensions of like adjacent units.

adjacent units, said wiper assembly being contained wholly within said housing and said sleeve having substantially the same mean axial length as said housing; and means including a sliding contact and an external terminal for making electrical connection with said wiper.

7. An interchangeable adjustable resistance unit adapted for assembly with other like units on a common continuous actuating shaft to form a multiple-unit adjustable resistance device comprising: a cup-shaped housing having an external peripheral clamping ridge at either end thereof; an annular resistance element disposed in said housing and provided with external connection terminals; and an electrical wiper assembly including a sleeve adapted for mounting on an actuating shaft and an electrical wiper mounted on said sleeve, said sleeve having approximately 180° segmental extensions on opposite ends thereof for engaging similar sleeve extensions of like adjacent units; and means including a sliding contact and an external terminal for making electrical connection with said wiper.

8. An interchangeable adjustable resistance unit adapted for assembly with other like units on a common continuous actuating shaft to form a multiple-unit adjustable resistance device comprising: a cup-shaped housing having an external peripheral clamping ridge at either end thereof; an annular resistance element disposed in said housing and provided with external connection terminals; and an electrical wiper assembly including a sleeve adapted for mounting on an actuating shaft and an electrical wiper mounted on said sleeve, said sleeve having complementary segmental extensions on opposite ends thereof for engaging similar sleeve extensions of like adjacent units, one of said segmental extensions including a resilient finger adjacent one edge thereof to eliminate backlash between adjacent sleeves; and means including a sliding contact and an external terminal for making electrical connection with said wiper.

9. A multiple-unit adjustable resistance device comprising: a continuous actuating shaft, a plurality of interchangeable resistance units, each including a cup-shaped housing having an external peripheral clamping ridge at either end thereof, an annular resistance element disposed in said housing and provided with external connection terminals, and an electrical wiper assembly including a sleeve adapted for mounting on said shaft and an electrical wiper mounted on said sleeve, said sleeve having complementary segmental extensions on opposite ends thereof for engaging similar sleeve extensions of like adjacent units, and means including a sliding contact and an external terminal for making electrical connection with said wiper, a clamping ring engaging each pair of adjacent housing clamping ridges; and a pair of end plates including shaft-supporting bearings.

10. A multiple-unit adjustable resistance device comprising: a continuous actuating shaft, a plurality of interchangeable resistance units, each including a cup-shaped housing having an external peripheral clamping ridge at either end thereof, an annular resistance element disposed in said housing and provided with external connection terminals, and an electrical wiper assembly including a sleeve adapted for mounting on said shaft and an electrical wiper mounted on said sleeve, said sleeve having complementary segmental extensions on opposite ends thereof for engaging similar sleeve extensions of like adjacent units.

adjacent units, and means including a sliding contact and an external terminal for making electrical connection with said wiper, a clamping ring engaging each pair of adjacent housing clamping ridges; a resilient driving connection between said shaft and only a terminal one of said sleeves; and a pair of end plates including shaft-supporting bearings.

11. A multiple-unit adjustable resistance device comprising: a continuous actuating shaft, a plurality of interchangeable resistance units, each including a cup-shaped housing having an external peripheral clamping ridge at either end thereof, an annular resistance element disposed in said housing and provided with external connection terminals, and an electrical wiper assembly including a sleeve adapted for mounting on said shaft and an electrical wiper mounted on said sleeve, said sleeve having complementary segmental extensions on opposite ends thereof for engaging similar sleeve extensions of like adjacent units, and means including a sliding contact and an external terminal for making electrical connection with said wiper, a clamping ring engaging each pair of adjacent housing clamping ridges; and a pair of end plates including shaft-supporting bearings, one of said end plates including means for restraining said shaft against axial movement.

12. A multiple-unit adjustable resistance device comprising: a continuous actuating shaft, a plurality of interchangeable resistance units, each including a cup-shaped housing having an external peripheral clamping ridge at either end thereof, an annular resistance element disposed in said housing and provided with external connection terminals, and an electrical wiper assembly including a sleeve adapted for mounting on said shaft and an electrical wiper mounted on said sleeve, said sleeve having complementary segmental extensions on opposite ends thereof for engaging similar sleeve extensions of like adjacent units, and means including a sliding contact and an external terminal for making electrical connection with said wiper, a clamping ring engaging each pair of adjacent housing clamping ridges; and a pair of end plates including shaft-supporting bearings, one of said end plates including provisions for mounting the device.

13. A multiple-unit adjustable resistance device comprising: a continuous actuating shaft, a plurality of interchangeable resistance units, each including a cup-shaped housing having an external peripheral clamping ridge at either end thereof, an annular resistance element disposed in said housing and provided with external connection terminals, and an electrical wiper assembly including a sleeve adapted for mounting on said shaft and an electrical wiper mounted on said sleeve, said sleeve having complementary segmental extensions on opposite ends thereof for engaging similar sleeve extensions of like adjacent units, and means including a sliding contact and an external terminal for making electrical connection with said wiper, a clamping ring engaging each pair of adjacent housing clamping ridges, the end member of each housing serving as a closure for the adjacent housing; and a pair of end plates including shaft-supporting bearings.

14. A multiple-unit adjustable resistance device comprising: a continuous actuating shaft, a plurality of interchangeable resistance units, each including a cup-shaped housing having an

external peripheral clamping ridge at either end thereof and having a peripheral flange and a complementary peripheral flange on opposite ends thereof for engaging similar housings of like adjacent units, and annular resistance element disposed in said housing and provided with external connection terminals, and an electrical wiper assembly including a sleeve adapted for mounting on said shaft and an electrical wiper mounted on said sleeve, said sleeve having complementary segmental extensions on opposite ends thereof for engaging similar sleeve extensions of like adjacent units, and means including a sliding contact and an external terminal for

5

making electrical connection with said wiper; a clamping ring engaging each pair of adjacent housing clamping ridges; and a pair of end plates including shaft-supporting bearings and having a peripheral flange and a peripheral recess complementary to and individually engaging corresponding adjacent peripheral flange and recess of said housings.
